AUTOMATIC TELEVISION SYNCHRONIZING APPARATUS

Aloysius J. Cawley, Pittston, Pa.

Application June 18, 1932, Serial No. 617,957

25 Claims. (Cl. 178—69.5)

This application is a continuation in part application of my application for Television, Serial No. 455,127, filed May 23, 1930, which is now U. S. Patent No. 2,026,610 of January 7, 1936 and of Serial No. 468,117, filed July 15, 1930 for Television, both of which disclose synchronizing apparatus.

The invention relates in general to the transmission of images by wire or wireless methods from one place to another. More particularly, it is concerned with the maintenance of a rotating element at a receiving station in absolute synchronism with a rotating element at a transmitting station without any attention on the part 10 of the operator. Some of the objects of the invention are as follows.

The maintenance of synchronism without the use of a separate wave channel or separate conducting circuit.

20 The production of synchronism by means of the regular television broadcast current by means of a periodic interruption in the latter.

A television scanning element provided with transparent segments bearing symbols or colors, 25 or both, or other identification means, which indicate the relative position of the rotating element at the receiving station with relation to a stationary light source which is illuminated at the time of interruption of the broadcast television current at the transmitting station.

The maintenance of synchronism by means of photoelectric cells and circuits in cooperation with transparent segments carried on a rotating scanning element, the photoelectric cells being 35 in cooperation with means for controlling the speed of the rotating element.

A rotatable scanning element bearing transparent segments and reflecting means in cooperative relation to said segments to reflect the 40 light traversing those segments into proper photoelectric cells.

An automatically controlled friction drive in cooperative relation with a rotatable scanning element, consisting of a friction wheel in adjustable contact or engagement with the scanning element, and electromagnetic mechanical means for adjusting the position of this friction drive with relation to the rotatable element, in order 45 to vary the speed of the rotatable element and thereby bring it into synchronism. A rotatable scanning element provided with transparent segments controlling the operation of photoelectric cells, and the latter controlling the operation of 50 electromagnetic, mechanical means for adjusting

a friction drive, a rheostat or other electrical motor controlling means.

Although the synchronizing apparatus is shown as being used with a television broadcasting system wherein the broadcast is periodically interrupted, thus rendering a separate wave channel unnecessary, the invention includes any of the synchronizing means in a separate wave channel without any interruption of the television broadcast.

10 A rotatable scanning element provided with a pair of electrical contact strips or segments having an insulated segment between them and a contact brush normally in contact with this insulated segment if the disk is in synchronism with a similar disk at the transmitting station. The contact segments acting to actuate an electromagnetic apparatus for altering the speed of the rotatable element, one of the segments bringing about acceleration of the speed and the other segment bringing about retardation of the speed of the rotatable element. The electromagnetic apparatus may also simultaneously or singly operate a rheostat controlling the speed of the motor.

15 A relay switch at the receiving station which acts to maintain the synchronizing circuit open for the greater part of the period of rotation of the scanning disk, the synchronizing circuit being closed for a brief interval corresponding to the period of interruption of the television broadcast at the transmitting station.

20 A stationary stroboscopic light source at the receiving station which illuminates the rotating element for a very short period corresponding to the period of interruption of the broadcast at the transmitting station. This gives the illusion of 25 the rotating element standing still in the position it occupies relative to the disk at the transmitting station as regards synchronism. This constitutes an excellent synchronism indicator.

25 A contact strip placed on the rotatable element at the receiving station at a point on the rotatable element or disk which will be directly opposite two stationary contact brushes when the rotatable element is in synchronism, the brushes being connected to a light source or an electromagnetic synchronism indicator. This also constitutes an excellent synchronism indicator.

30 Also, light sources or electromagnetic indicating means in cooperative relation with the contact segments carried upon the rotatable element whereby, as the latter are actuated, either a light is flashed or else a pointer indicates whether the rotatable element is ahead of or behind synchronism.

55

An adjustable friction drive provided with a lever controlled by electromagnetic means, the lever also acting to operate a motor controlling rheostat or other controller.

5 A centrifugal speed controlling means acting in conjunction with a friction speed drive to further regulate the speed of the rotatable scanning element.

10 A switch operated by the centrifugal speed control means whereby the synchronizing current is not turned on until the speed of the rotatable element has reached a speed approximating synchronization.

15 An electrical switch operated by the centrifugal speed governor controls the speed of the motor either by means of a rheostat or other motor speed controlling means.

20 A rotatable scanning element consisting of a flat disk to which lenses or prisms, or the like are cemented, the disk being coated with opaque paint or the like. Such a disk is very easily and cheaply manufactured as compared to an ordinary scanning disk employing lenses, or even those employing holes for scanning purposes.

25 A driving means consisting of a motor provided with a hollow shaft of irregular cross section, which accommodates a shaft of irregular cross section, the latter being attached to a centrifugal governor. A variable speed friction drive 30 wheel is carried on inner shaft. The variable speed friction drive and the centrifugal governor thus act jointly to maintain the apparatus in synchronization and at constant speed.

35 Other advantages and objects of the arrangements will be apparent from a consideration of the following specification and claims when read in connection with the accompanying drawings wherein the various figures thereof represent in a conventional manner the principles covered by 40 the invention.

45 Figure 1 is a front elevational view of a scanning apparatus which is provided with means for indicating synchronization consisting of a light mounted on said disk.

50 Figure 1a is a side elevational view of the apparatus shown in Figure 1.

55 Figure 2 is a front elevational view of a scanning apparatus provided with a photoelectric synchronizing apparatus.

50 Figure 3 is an elevational view of the interrupting apparatus at the transmitting station, shown in Fig. 2 in part.

55 Figure 4 is a side elevational view partly in cross section of the scanning apparatus shown in Figure 2 in part.

60 Figure 5 is a front elevational view of a scanning apparatus provided with synchronizing means consisting of a variable speed friction drive controlled by photoelectric means. Fig. 5a is a view of the apparatus shown in Figure 5 with a motor rheostat control added.

65 Figure 6 is a side elevational view of the apparatus illustrated in Figure 5.

concentric shafts of the synchronizing apparatus.

Figure 9 is a front elevational view of a modification of Figure 8.

5 An apparatus for indicating synchronization between a receiving station and a transmitting station is illustrated in Figure 1. No separate wave channel is required for the attainment of synchronization. At the transmitting station the broadcasted television waves are interrupted during a short portion or period of each revolution of the scanning disk. As in most television systems, a revolution of the disk generally completes a single picture, it necessarily follows that after each image is televised, there is a very short interval during which no broadcast takes place. This does not introduce any more serious difficulty or defect than that already existing in ordinary motion pictures, as there, between images there is a short interval of darkness during which the film is shifted.

10 The standard Nipkow disk is mounted as shown at 1 upon shaft 4. The holes or lenses in this disk are shown at L. The neon, or other glow lamp 2 is shown in cooperation with the image area in the usual manner. Collector ring 3 is mounted upon shaft 4 but insulated very carefully from it. Brush b makes contact with this ring, while brush c makes contact directly with the shaft 4. The synchronizing lamp g is mounted upon the disk 1 and is in electrical connection by means of wires a and e with the shaft 4 and the collector ring 3. The broadcasted television current, after being amplified, is supplied to the neon lamp 2 by means of the wires 35 A and B. Part of this current is shunted to the synchronizing indicating lamp g by means of wires n and o. As before stated, the television broadcast is interrupted for a short interval during each revolution at the transmitting station. 40 Assuming that this interruption is arbitrarily selected as at the extreme lower portion of the orbit of the lamp as indicated by i, then, if the receiving disk is in synchronization with the sending station disk, the scanning lamp g will describe a path of light p which is interrupted at i. If the receiving disk 1 should be in isochronism with the transmitting disk, then the point of interruption in the path of light p will be either to the right or to the left of the position 45 shown in Figure 1. For instance, if the receiving disk (shown in the figure) is in advanced isochronism, the point of interruption in the path p will be anywhere between g and the glow lamp 2 in the left half of the circle. If the disk is in retarded isochronism, the point i will be anywhere between g and the lamp 2 in the right half of the circle. If the receiving station disk is in asynchronism with the transmitting station disk, then as the interruptions are occurring at 50 different points during each revolution, no clear distinct interruption will be discernible, and there will be no gap i in the path of light described by the synchronizing lamp g. The lamp g, since it 55 flashes only during a small portion of the revolution period of the disk 1 and since the disk makes about twenty revolutions per second, constitutes the equivalent of a stroboscope with the rotating disk 1. If the disk 1 is in absolute synchronization, there will always be a dark area at i, and the path p, consisting of a broken circle will appear stationary. The synchronizing lamp g takes a very small amount of the television broadcast current, as it is made very small.

60 Figure 1a is a side elevational view of the apparatus shown in Figure 1. Figure 2 is a front elevational view of a scanning apparatus provided with a photoelectric synchronizing apparatus. Figure 3 is an elevational view of the interrupting apparatus at the transmitting station, shown in Fig. 2 in part. Figure 4 is a side elevational view partly in cross section of the scanning apparatus shown in Figure 2 in part. Figure 5 is a front elevational view of a scanning apparatus provided with synchronizing means consisting of a variable speed friction drive controlled by photoelectric means. Figure 6 is a side elevational view of the apparatus illustrated in Figure 5. Figure 7 is a front elevational view of a scanning apparatus provided with a variable speed drive in conjunction with electric contact elements carried on a rotatable disk. Figure 7a is a modification of part of the friction drive. Figure 7b is a cross section of a special scanning disk. Figure 8 is a front elevational view of a scanning apparatus employing a variable speed friction drive and a centrifugal speed governor. Figure 8a is a cross sectional view of the two

ratus illustrated in Figure 1. The reference characters have the same meaning. The apparatus illustrated and described in connection with the above two figures discloses merely a synchronism 5 indicating means.

Figure 2 illustrates another modification, which includes means for maintaining the disk in synchronism with the disk at the transmitting station. The television broadcast is received by 10 the usual wireless apparatus including an antenna and is illustrated at *d*. An amplifying apparatus is shown at *K*, which intensifies the broadcast current as much as possible. Wires *E* and *D* conduct the amplified current to the glow lamp *2*, 15 which is shown in the usual cooperative relation with the scanning disk *1* provided with holes or lenses *L*. A portion of the amplified current is shunted by the wires *F* and *G* to the relay *R*, which acts to open a circuit including a synchronizing lamp *7*, shown in dotted lines on the 20 opposite side of the disk *1*. The current at the transmitting station is interrupted for a short interval during the revolution of the disk at the transmitting station. This interruption will take 25 place at a definite, prearranged point of the path of rotation of the disk, and is indicated in the figures of this application at the extreme lower portion of the circle described by the disk. The relay *R* is so designed that it will respond readily 30 to a vibration rate of twenty per second. The conventional representation of a relay is shown, however, the armature of the relay together with its spring or other equivalent is such that it will readily vibrate at the frequency of television 35 image change, which is from ten to twenty per second according to the degree of continuity of image that is desired. When the broadcast is being received, the armature of the relay *R* is attracted towards the electromagnet and the circuit composed of the wires *H* and *I*, the source 40 of power *P* and the lamp *7* is opened. However, during the short interval of a revolution that the broadcast is interrupted, the lever of the relay *R* is released and is attracted by its spring 45 (not shown) to the right and the above circuit is closed. The lamp *7* is then illuminated. Disk *1* is provided with two transparent segments *5* and *6*. Those transparent segments are separated by a relatively small portion of opaque disk. This 50 latter is shown as just covering the lamp *7*. Therefore, when the receiving disk is in synchronism with the sending disk, the lamp *7* is illuminated only when the short opaque space between the two transparent segments is just in front 55 of the lamp, and its light cannot be seen. Synchronism is, therefore, indicated by absolute darkness. If the disks are rotating in isochronism and the receiving disk is behind the transmitting disk, then the transparent segment *5* will 60 encroach upon the lamp *7* and be interposed between the lamp and the observer. The result is that the light of the lamp will be seen. The segment *5* may be colored red, or any other color, and the appearance of this color will indicate 65 that the disk is behind the transmitting disk. In addition, reference characters, such as numbers indicating the number of degrees the receiving disk is behind the sending disk may be added, as for instance 45 shown in the figure, when it is 70 in position opposite the light it will show that the disk is 45 degrees behind. The arrow turned backward in relation with 45 indicates that the disk is behind. 45 and the arrow, therefore, indicate that any reference characters may be 75 placed on the transparent segments that one

may desire. Transparent segment *6* may be colored blue and suitable reference characters printed upon it. The segments may be made much smaller, i. e., only a little larger than the diameter of the shaft *4*, if desired. Smallness is desirable, as the speed of the brushes in contact with the collector rings in the modifications to be later described, will thereby be greatly reduced. The segments are shown as increasing in width as the distance from the opaque portion increases. The object of this is to increase the amount of light that reaches the photo cells (to be described shortly) the farther the disk is out of synchronism, and therefore to correct the asynchronism as quickly as possible. The segments may increase uniformly in width, instead of in a stepped manner as illustrated. As the lamp *7* is only flashed on for a short interval of time, and as this interval is always in accordance with the time during which a certain portion of the disk is successively opposite the lamp *7* during each revolution, at virtually the same point, a stroboscopic effect is produced. Suppose that 45 is opposite the lamp *7* at each revolution, then it will be seen as stationary at that point. The same is true of any other reference character at any other point on the disk if that particular point is opposite the lamp *7* during a series of successive revolutions. As synchronism is established by proper adjustment, the character 45 would move to the position shown in the illustration from that in front of lamp *7*. Thus the degree of advanced or retarded isochronism is readily determined by this apparatus. The segments *5* and *6* need not be of a size equal to approximately a semicircle, as shown, but may be much shorter. For instance, they may be only 45 or 90 degrees in extent.

Automatic synchronism may be attained in several different ways. By one method, photo-cells *P* and *P'* are arranged to be excited, depending upon whether the disk is in advance or behind that at the transmitting station. A prism *r*, or a series of such prisms is placed over the windows or transparent segments *5* and *6*. That over window *5* is illustrated by dotted lines in Figure 3, which illustrates the fact that the light is reflected downward into the photoelectric cell *P'*. Segment *6* has a prism *rb* placed over it with its base turned inwards towards the center of the circle. This is illustrated in Figure 4 and shows that the light is reflected upwards into photocell *P*. The photocells are shown as being of the cylindrical type. It is to be noted that the width of the transparent segments *5* and *6* increases towards their opposite ends. The result is that, the greater the disk is out of synchronism, the more light that will be admitted to the photocell and the greater the corrective response brought about by the circuits associated with the cells. Accordingly, the wire *T* leads to an accelerating means, while the wire *S* leads to a retarding means. If the disk is behind, cell *P'* is actuated and the accelerating means brought into play, while if the disk is ahead, cell *P* is actuated and the retarding means brought into play. Wire *C* is a common return wire for both circuits, i. e., accelerating and retarding.

Figure 4 illustrates the fact that the disk *1* may be made of any transparent material, such as 70 Bakelite (transparent) plate glass, or other, and the prisms *r* and *rb* cemented to them. The prisms *r* and *rb* may be arranged side by side segmentally over the entire extent of the transparent sections *5* and *6*. The cement used for at- 75

taching the disk and the prisms or other optical elements, such as lenses, may be Canada balsam. Lens making, prism making and plate glass making have all reached the dignity of fine arts. They are almost perfect. The lenses, prisms and plate glass can therefore be made very cheaply and accurately. It is only necessary to cement the various optical elements to the disk. A very desirable combination is that of a disk made of transparent Bakelite to which cylindrical lenses, or other optical elements are cemented. This gives a disk which is of itself very light, but the peripherally located lenses lend peripheral weight which will develop when in motion a desirable centrifugal force which will tend to maintain the disk in uniform motion. The portions of the disk which are unoccupied by lenses, prisms, etc., may be painted by means of dark, opaque paint. Thus the expense of drilling holes in a disk in order to mount the lenses is dispensed with. Another desirable quality of the Bakelite disk is that it is not nearly so fragile as glass, consequently, a much thinner disk may be used.

Figure 5 illustrates another modification of the invention and also shows a means of correcting asynchronism by means of an electromagnetic arrangement. The amplified television current, whether received by wire or wireless means, is conducted by wires A and B to the neon or other glow lamp 2 and also to the relay R. The scanning disk 1 is here shown as being provided with transparent segments of different sizes, i. e., they are segments of circles of different diameters in order that each operates a different photocell 35 without using prisms. Each transparent segment can only be opposite its own specific cell, and can never be opposite the other cell. The television broadcast is interrupted periodically at the transmitting station during a very short 40 interval during each revolution of the disk, as before stated. The point in the revolution of the disk at which this interruption may take place will be agreed upon by the various broadcasting companies, but it is here shown (according to 45 the position of the disk at the receiving station, which is illustrated) as taking place when the opaque portion located between the two transparent segments is at its extreme lower position. As before explained, the circuit containing the 50 source of power Pr and the synchronizing glow (or other) lamp 7, which are connected by the wires H and I, is broken during the period of interruption of the television broadcast from the central station. If the receiving disk 1 is in absolute synchronism with the transmitting station disk, then the lamp 7 will be illuminated only 55 while the opaque portion between the two transparent segments is directly opposite the lamp, and no light will be seen. Two cylindrical photoelectric cells P and P' are placed directly opposite the lamp 7. If the disk 1 is in synchronism with the disk at the transmitting station, neither cell will receive any light. If the disk 1 should lag behind the disk at the transmitting station, then 60 transparent segment 5 will be found opposite the lamp 7 when it is illuminated and the light will enter photoelectric cell P. Depending upon the type of cell (the speed of response of selenium cells has been greatly increased of late) either 65 current will be permitted to flow, or in the vacuum tube type of cell a small current of electricity will be generated in the cell and this will be amplified by the amplifying or power circuit Pr', and the solenoid 8 will receive this current and tug 70 at the armature attached to lever I, with the

result that the jaw J since the lever is pivoted at f, will move to the right. The motor M is shown as provided with a square, or rectangular, or other irregular cross section shaft u. The wheel W is 5 slidable laterally on this shaft but cannot rotate upon it. It will be seen that the jaw J moves the wheel W with which it engages, towards the center of the disk 1. This means, obviously, that the speed of the disk will be increased. Pr represents any desirable source of power or amplifying 10 means. If the disk 1 should gain over the speed at the transmitting station of the disk located there, then transparent segment 6 will be opposite the lamp 7 when it is illuminated and its light 15 will reach the photoelectric cell P' with the result that solenoid 9 will be actuated and a tug at its armature attached to the lever I will cause the jaw J and wheel W to move to the left towards the periphery of the disk 1, resulting in a reduction of 20 the speed of the disk. The flashes of the lamp 7 take place about twenty times per second or more if the best television reception is to be attained. However, a lower speed may be used. The wheel W is mounted upon shaft u in such manner that 25 it must rotate with the shaft. It is slidable upon the shaft and can therefore be shifted to new positions. The friction wheel W engages with the disk 1 which is provided with a suitable surface to prevent slippage, such as leather, rubber, etc. The wheel W may be provided with a peripheral 30 ring of adherent material such as leather or rubber as shown more clearly in Figure 6. If desired, a special friction disk may be attached to disk 1. As the transparent segments 5 and 6 are 35 provided with reference characters, such as those described in connection with Fig. 2 above, and since the light is flashed on during a very, very small fraction of a second and repeated about twenty times per second, the particular reference character will be seen opposite the light and will 40 be perfectly legible, as the light is extinguished during the time that this particular character moves around with the revolving disk. The reference character will apparently be standing still 45 due to this stroboscopic effect. It is to be noted that there is a constant adjustment of the position of the wheel W relative to the shaft u. Just as soon as there is the slightest deviation from 50 synchronism the corresponding photoelectric circuit is actuated and the friction wheel W is shifted to a position to correct this deviation. This operation is carried out in a purely automatic manner. The motor M may be a synchronous motor when the question of synchronism is mostly involved in a correction of isochronism or a conversion of isochronism into synchronism. The 55 motor may be a phonic motor. The motor M may be provided with an independent speed governing apparatus so that its speed is constant, as illustrated in Fig. 5a. However the present disclosure is concerned with means for keeping the scanning disk in cooperative relation with any type of motor in absolute synchronism without any attention whatever on the part of the operator. This feature will be described in greater 60 detail in connection with later figures.

Figure 6 is a side elevational view of Figure 5. The television broadcast is received by the wireless apparatus d and amplified by suitable circuits at K and the amplified current led to the 70 neon or other lamp 2 by wires A and B and to the relay R. The relay breaks the circuit containing the amplification or power element Pr, which is connected by the conductors H and I to the synchronizing lamp 7. This lamp is there- 75

fore, only illuminated during a very small portion of the revolution of the disk 1. Disk 1 is mounted upon the shaft 4; the latter is supported by two strong bearings. The friction wheel W with its peripheral ring of adherent material is shown mounted upon the shaft u of irregular cross section, which is here shown as square. However, a very desirable cross section of a shaft would be a rectangle. Another form 10 would be that of a cross. The motor M rotates the shaft u and the friction wheel W. The latter engages with the surface of the disk 1, which also may be provided with an adherent surface. The 15 lever l with its fulcrum is clearly shown with its jaw J engaging the wheel W. It is to be noted that the lever l should be designed to be perfectly balanced so that it will stay in any position in which it is placed. The invention is not limited to this feature of the lever however. The 20 synchronizing lamp 7 is shown opposite to the two photocells, one of which is designated P. The accelerating solenoid is shown at 8. The photoelectric cells are shown as being of the cylindrical type.

25 The lever l may, in one modification be that of a rheostat governing the speed of the motor M. This may be used in an arrangement where-in the motor M is directly attached to the shaft 4 upon which the disk 1 is mounted. Or, the arrangement shown in Figure 5a may be used and in which the lower half of the lever l constitutes virtually the arm or crank of a rheostat ra, or actuates such a rheostatic arm or crank. Or it 30 may actuate any type of motor speed control.

35 A modification of the invention which dispenses with the use of photoelectric cells in the synchronizing circuits is illustrated in Figure 7. The television broadcast current is led into the amplifying apparatus K by means of the wires 40 A and B. The amplified image varied current is then supplied to the neon lamp 2 and the second amplifying apparatus K'. The current is then supplied to the relay R. The conductors E and D connect the glow lamp 2 in circuit. The Nipkow disk or its equivalent is shown at 1. The 45 holes or lenses are shown at L and are arranged in a spiral line in the usual manner. Instead of the transparent segments described in connection with the previous figures, two contact strips 5a and 6a are attached to the disk 1. Those strips are shown of varying width, which is shown as increasing progressively from the lower end of the strips to the upper in the figure. The object of this is to provide a greater contact area to the various brushes V and thus to furnish a 50 greater current to the synchronizing circuits in proportion to the degree of asynchronism present. A single wide brush or a plurality of smaller or narrower brushes may be provided at V. 55 If brushes of high resistance are used, the varying area of contact of 5a and 6a will cause correspondingly varying amounts of electric current to pass. As described in connection with the previous figures, the broadcast current is 60 periodically interrupted at the transmitting station at a predetermined point of the revolution of the transmitting disk. This is for the present disclosure assumed to be at the lowest point in the circle described by the rotating disk. Consequently, the apparatus illustrated in Figure 7 65 is in a position that it should occupy when the disk 1 is in synchronism with the transmitting disk. The interrupted broadcasted image current has permitted the relay to move its armature to the left and close the circuit through the

battery. However, since the disk 1 is in synchronism with that at the transmitting station, the brush V rests upon the nonconducting interval between the two contact strips 5a and 6a and no current can pass from the battery Y or 5 other source of power. The glow lamp U is connected to wire 10 which is in turn connected to the relay R so that when the latter closes the synchronizing circuit, even though no current flows through the contact strips, still the lamp 10 U will be momentarily illuminated for its stroboscopic effect of illuminating the disk which may have various symbols located upon it indicating its position as regards synchronism. In 15 fact, the position of the contact elements themselves thus serve. The lamp U may be a glow lamp of any desired type, but is not limited thereto. The disk 1 is supposed to be made of some insulating material, such as Bakelite. However, if it is made of metal it should be covered with 20 a disk of insulating material upon which the contact strips 5a and 6a are mounted.

Suppose the disk 1 is lagging behind the transmitting disk, contact strip 5a comes in contact with the brush V, and the battery or other current passes from Y to the relay switch R to wire 10, to brush V to contact strip 5a to wire s to collector ring w, to brush X and by wire to the solenoid 8 which exerts a torque upon the armature of the lever l which is pivoted at f. The 30 current returns from the solenoid 8 to the battery or other source of power Y. The motor M is provided with a shaft of irregular cross section, as already explained and has the slideable wheel W mounted upon it. The wheel W makes 35 frictional contact with the disk 1 and drives it. When the solenoid 8 attracts the armature attached to the lever l, it causes the clutch J to move the wheel W towards the center of the disk 1, with the result that a greater speed is imparted to the latter. If the disk 1 is gaining 40 on the transmitting disk, then contact strip 6a will engage with brush V and the current will pass from the battery Y to the relay R, to wire 10, to brush V, to contact strip 6a, to wire t, to collector ring v, to brush Z, to solenoid 9 and back to Y. The solenoid causes the lever to be moved to the right with the result that the jaw J moves to the left and the wheel W is shifted 45 towards the periphery of the disk 1 which reduces the speed of the latter. There is thus a 50 constant automatic effort on the part of the synchronizing apparatus to keep the disk in absolute synchronism. No attention is required on the part of the operator and this is true regardless of the type of motor used. Although no 55 separate synchronizing current is required with the disclosed apparatus, still the invention covers the use of the apparatus in a separate synchronizing current arrangement. The attainment of 60 synchronizing by the interruption of the broadcast of the television is an invention over the employment of a separate synchronizing wave channel or separate synchronizing circuit, if the apparatus is used with wires. The invention 65 therefore, covers the use of the apparatus with a separate wave channel or circuit.

The wheel W may be provided with means for holding it more securely in the position on the shaft in which it is placed, and at the same time 70 being readily shiftable to a new position by the jaw or clutch J. Figure 7a shows the wheel equipped with very delicate flexible strips of metal 75 which make contact with the shaft u. The flat face of the shaft u may be roughened or pro-

vided with fine ridges as shown at 22, which are depressed below the surface of the shaft *u* in order not to interfere with the movement of the wheel *W*. The lever *l* should be well balanced with regard to its fulcrum *f*, just as the arm of a balance, so that it will have a tendency to remain at rest in any position in which it may be placed. A handle *h* is shown for manual adjustment of the position of the wheel *W* in order to manually attain synchronism, if desired.

The disk *l* may be made of plate glass or transparent Bakelite. The lenses *La* may be of glass and plano-convex and their flat surfaces cemented to the disk *l*. The portions of the disk which are unoccupied by any lens or other optical element may be painted with an opaque paint or its equivalent. A transparent Bakelite disk *l* with glass prisms and lenses is a good construction. The expense of boring holes in the disk to accommodate the lenses or other optical elements is done away with. In manufacturing such a disk, a form is made which consists of a flat board, or the like, having spherical depressions located therein and the depressions arranged in a spiral. The lenses are simply placed in those depressions, which they fit snugly and their flat, upturned faces coated with a suitable cement, such as Canada balsam. The disk *l* is then laid upon this flat surface including the cement covered lens surfaces and left to harden, when it is removed together with the firmly adherent lenses. The cost of manufacture is thus greatly reduced. If such a disk were moulded of glass, for instance in one piece, the lenses (since they are molded) would be unsatisfactory from an optical standpoint. To grind the lenses which have been cast in one solid piece with the disk would be prohibitive and almost mechanically impossible. By the present method, the lenses have been manufactured in accordance with the best principles set down by optical manufacturers, the same is true of the plate glass or the Bakelite disk. The disk and the optical lenses or other optical elements are then combined by the simple process of placing the lenses in the depressions in the form and simply coating their upturned faces with cement and the disk laid on. All of the expense of "laying out" the spiral, boring the holes in the disk and fitting the lenses into the holes is dispensed with. Obviously a disk made of Bakelite with cemented lenses could not be moulded in a single piece. This is a very desirable embodiment of the invention. After the disk is formed, the unoccupied portions are coated with opaque paint.

Another modification of the invention is illustrated in Figure 8. The motor is shown at *M*. It is provided with a hollow shaft *ua* of square, rectangular or other irregular cross-section. The square or other irregular cross-sectioned shaft *u* fits into this hollow shaft and is unrotatable relative to the shaft *ua*. It may be readily slid in and out of the hollow shaft *ua*. The shaft *u* turns in the journal *l7* and it is here of a round cross section to accommodate the journal bearing surface. The shaft is further journalled at *l7a*. A centrifugal governor *l6* of any desired well known type is shown in cooperative relation with the shaft *u*. As the speed increases, the balls fly outward from the shaft in the well known manner. In so doing they pull the shaft *u* towards the left and consequently shift the friction wheel *W* to the left, or towards the periphery of the disk *l* with a resultant decrease of the speed imparted by the shaft *u* to the disk *l*. The shaft, it is to be noted is rounded for some distance from the bear-

ing *l7* in order to permit it to shift or slide through the journal bearing. The end of the shaft *u* will project farther and farther to the left beyond the journal *l7a* as the speed is accelerated. All of the shaft that passes through the governor *l6* is rounded. Thus a centrifugally operated speed governor is added to the previously described apparatus. If desired the governor *l6* may have attached to it the contact brush *23* which makes contact with the contact point or strip *25* when the motor has been brought up to full standard synchronizing speed. The brush and contact strip are connected to the synchronizing circuits in such manner that contact is not made between *23* and *25*, and consequently the latter are not energized until full speed has been attained by the motor *M* and wheel *W*. The disk *l* is shown in synchronism with the transmitting disk and at the point it should occupy if it is in synchronism with the transmitting disk when the broadcast is interrupted. The relay *R* has closed the circuit and the current passes from the battery *Y* to relay switch *R* to brush *V* to contact strip *y*, to brush *x* to electromagnet *19* by means of wire *l6a* and back to *Y*. The armature-indicator *l5* is attracted to its position indicating synchronism on its dial (not shown). It will be noted that the contact metal or other conducting strips *5a* and *6a* are made much smaller than those previously shown. If the disk *l* is lagging behind the transmitting disk, then the strip *5a* is in contact with the brush *V* during the time that the relay *R* closes the circuit and the current passes through strip *5a* to collector ring *w* to brush *X* to electromagnet *19*, which attracts the armature-indicator *l5* to the position indicating retarded isochronism. If the disk *l* is running ahead of the transmitting disk, then contact strip *6a* makes contact with brush *V*, and the current passes from *Y* to relay switch *R*, to brush *V*, to collector ring or contact strip *6a*, to brush *Z*, to electromagnet *20*. The latter attracts the armature-indicator *l5* to the position indicating advanced isochronism or accelerated asynchronism. The current then passes from *20* to the solenoid *9*, which attracts the armature attached to lever *l* and pulls the latter to the right with a resultant shifting of the wheel *W* by means of the clutch *J* towards the periphery of the disk *l*, and the latter is slowed down. In the former case, where the disk *l* was running behind the transmitting disk, the current returned from the electromagnet *19* to the solenoid *8* and from thence to the source of power *Y*. The solenoid *8* attracted the armature attached to lever *l* to the left, with a consequent shifting of the wheel *W* to the right and towards the center of the disk *l* with a resultant speeding up of the latter. Thus a means is provided for indicating by means of a pointer and dial, the character of asynchronism, isochronism or synchronism that may exist at any time.

The jaws of the clutch *J* are turned down in the plane of the paper and two wheels *Ja* are rotatably supported on small shafts that are attached to the turned down ends. The wheels *Ja* may be coated with a ring of leather or rubber or other adherent surface. The purpose of those wheels is to eliminate the friction that would otherwise exist between the clutch *J* and the wheel *W*.

The synchronism indicator consisting of the elements *15*, *18*, *19* and *20* may be omitted if desired. It is a very convenient and useful part of the apparatus, however.

The solenoids *8* and *9* in conjunction with the lever *l* operate the friction drive *W* for the pur-

pose of maintaining synchronism. However, in one modification of the invention, the lever *l* may be used to operate a rheostat or other speed controlling means governing the speed of the motor *M*. In another modification, the lower end of the lever *l* may be arranged to operate a rheostat, or other motor controlling means in connection with motor *M*. Thus then, the solenoids and lever would control the speed by means of the friction drive and motor current control, while the centrifugal governor *16* would regulate the speed from a standpoint of momentum. A very important function performed by the governor *16* is to correct the irregularity of speed in an electric motor known as "hunting", which is well known and understood to those skilled in the art.

Figure 8a illustrates a cross section of the two shafts *ua* and *u*. The hollow shaft *ua* is shown as provided with roller bearings *ra*, which fit closely to the inner shaft *u*. Thus the two shafts are absolutely unrotatable relative to each other, and yet shaft *u* may be slid in and out of the hollow shaft *ua* with very little resistance, due to the roller bearings.

In the operation of the apparatus, the solenoids and lever *l* act to maintain synchronism between the transmitting disk and the receiving disk *l*. They are constantly at work correcting all irregularities of synchronism. They cannot, however, correct the speed irregularity known as "hunting" and it is principally for the correction of this irregularity that the centrifugal governor *16* is provided. It is to be noted that the lever *l* shifts the wheel *W* on the shaft *u*, while the governor *16* shifts the shaft *u* and wheel *W* as a single unit. There is therefore, no interference between the operation of those two speed controlling elements.

The brush *23* attached to the centrifugal speed governor and the contact *25* may be connected in the synchronizing circuit between *Y* and *R* as illustrated in Fig. 9, and the latter will thus not be operative until the disk has been brought up to approximately synchronizing speed under control of the centrifugal governor *16*. The contact *25* is shown as a strip, but it may be a button, thus making contact for a shorter interval of speed variation. The end of the governor *16* adjacent the bearing *17a* is provided with a groove into which a tongue forming part of *17a* projects and thus holds the ring of the governor always adjacent the bearing *17a*. The shaft *u* is therefore, pulled to the left as the speed increases. However, the position of the motor *M* and the governor *16* might be reversed as shown in Figure 9, and in that case, the ring of the governor adjacent *17a* would not be attached thereto while it rotates. Instead, the ring of the governor *16* adjacent the bearing *17* would always be in contact therewith, and the opposite end or ring of the governor would move with the variations in speed. An increase of speed would then push the shaft away from the governor, and the wheel *W* would be pushed peripherally with a decrease of speed, since the position of the motor *M* and the governor *16* would be reversed. Many other modifications readily suggest themselves to those skilled in the art, and they are all within the spirit of the invention.

Attention is called to the fact that although the impulses in the synchronizing circuit are of short duration, still they are repeated at the rate of twenty per second and are somewhat similar to a Faradic current and possess a cumulative effect while they last. As previously mentioned, a separate wave channel might be used instead of de-

pending upon the interruption of the television broadcast to maintain synchronism.

The arrangement of the transparent or conducting segments with the opaque or insulating segment located at the lower portion of the various figures of the drawings is such that it might be regarded as a means of determining the position of the disk during the stroboscopic illumination of the disk. (The upper portion or interval between the two segments may be much closer, in fact the contact segments are placed as nearly as possible to each other without actually making contact with each other.) This arrangement may therefore be regarded as a position indicating arrangement, as it indicates the position in which the disk is located during the momentary illumination produced by the intermittent synchronizing current.

Many modifications of the relationship of the centrifugal speed governor to the disk are possible. For instance, Figure 8 may be regarded as turned on its right side, when the centrifugal governor would be found to be located at the top of the revolving disk. The operation would then be such that when the balls are centrifugally rotated outward, the shaft is permitted to drop downward through the journal *17*. The wheel *W* then, instead of being located in the upper half of the disk as illustrated in the figure, would be in contact with the lower half of the disk. Then, when the increased speed rotated the balls or other centrifugal elements outwards, the wheel *W* would be lowered to a point nearer the periphery of the disk and the speed slackened. Many other modifications readily suggest themselves without departing from the spirit of the invention.

In another modification, the jaw *J* might be placed on guide rods, as described in my application Serial No. 468,117 of July 15, 1930, and an armature fastened to the jaw. The solenoids *8* and *9* or their equivalents would be placed in co-operative relation with a pawl and ratchet, by means of which it would be moved to new positions.

The disks shown in the various figures might be regarded also as the disk portion of a cylinder-disk scanning element, the scanning holes or lenses being carried on the cylindrical surface, while the synchronizing elements would be carried on the disk portion of the element.

Although the synchronizing apparatus is shown in the figures as being arranged to operate during the time that the television broadcast is interrupted, it is to be distinctly understood that a separate wave channel or a separate circuit may readily be used without departing from the spirit of the invention.

The brush *23* in Figure 8 is supposed to be mounted upon a pair of stationary guides and engages in a groove in the ring of the governor *16*. However, many modifications suggest themselves. For instance, the end of the lever or shaft *u* moves to the left of the journal *17a* to various extents depending upon the speed. One or more fulcrumed levers having one of their ends in firm contact by means of a spring or the like against the end of the shaft may be used for the operation of speed controlling means whether rheostats or other. Their free ends may constitute part of a rheostat arm, or may be in contact with various contact segments of speed controlling means.

The present disclosure is especially concerned with the maintenance of synchronism of television

sets in isolated places where no synchronous motors operated by conventionally phased currents are available. In cases where a motor is operated by a dry or a storage battery, means are disclosed whereby the set is maintained in synchronism without any attention on the part of the operator other than initially turning on the current. The rheostatic control of the motor by means of the centrifugal governor will correct speed variations due to battery deterioration or other change.

At the transmitting station, as illustrated in Fig. 3, the disk or other rotatable element 1 would be provided with a contact segment R1 consisting of a circle which would be broken at a point corresponding to the opaque or insulating segment in the various figures. It would be similar to the path "p" of Figure 1. A collector ring R2 of any type would also form part of the rotating element and be connected to the segment by conductor C3. The broadcasting current would be supplied to the contact segment by brush b2 and taken from the collector ring by brush b1. This would produce the desired interruption.

In Figure 8, contact strip y and associated brushes may cause a light to be illuminated instead of the indicator 15 and 19. Moreover, this light may have a specially significant color.

The relay R covers any known means of interrupting current.

Having described my invention, I claim as new and desire to secure by Letters Patent:

1. In combination: means including a rotatable element for reproducing a television image from an image varied current, a pair of transparent segments on said rotatable element the width of said transparent segments being progressively increased in order to increase their asynchronism correcting function, an opaque segment separating said transparent segments, a stationary light source in cooperative relation with said transparent segments and said opaque segment and means connected with said light source for illuminating said light source only during a portion of the revolutionary period of said rotatable element and when said opaque segment is opposite to and obscuring said light source when said rotatable element is in synchronism, said light source being when illuminated opposite to either of said transparent segments during asynchronism.

2. In combination: means including a rotatable element for reproducing a television image from an image varied current, a pair of transparent segments on said rotatable element, an opaque segment separating said transparent segments, a stationary light source in cooperative relation with said transparent segments and said opaque segment and means connected with said light source for illuminating said light source only during a portion of the revolutionary period of said rotatable element and when said opaque segment is opposite to and obscuring said light source when said rotatable element is in synchronism, or when either of said transparent segments are opposite said light source when said rotatable element is in asynchronism and a pair of photoelectric cells, each of said cells being in cooperative relation with one only of said transparent segments to be influenced by the light of either of said transparent segments during asynchronism of said rotatable element said cells being connected to synchronizing apparatus.

3. A synchronism indicating apparatus consisting of means including a rotatable element for

reproducing an image from a periodically interrupted image varied current, two transparent segments carried on said rotatable element, an opaque interval separating said transparent segments, said opaque interval being opposite a 5 definite point when said element is in synchronism, a stationary light source at said definite point and in cooperation with said transparent segments, means for illuminating said light source, electrical means actuated by said image 10 varied current for illuminating said light source only during the period of interruption of said image varied current and a pair of photoelectric cells on the side of said rotatable element opposite said light source, each of said cells being 15 adapted to be energized by the light of said source when said transparent segments permit the light of said source to reach its specific cell and a speed adjusting means in cooperative relation with said cells and said rotatable element whereby 20 synchronism is maintained.

4. In combination: a rotatable element, means in cooperative relation with said rotatable element for reproducing an image from an image 25 varied current, the different portions of the surface of said rotatable element being rotatable at different uniform speeds, a variable position rotatable driving means in cooperative relation with said rotatable element making driving contact with any of said portions of said surface to 30 drive said element at any desired uniform speed and photoelectric means in cooperative relation with said rotatable element and said variable position rotatable driving means said photoelectric means including light influencing means 35 borne on said rotatable element and a stationary photoelectric element in cooperation therewith by means of which the position of said driving means is varied in order that speed of said rotatable element is adjusted to attain synchronism and isochronism. 40

5. In combination: means including a rotatable element for reproducing an image from an image varied current, the different portions of the surface of said rotatable element being rotatable at different uniform speeds, a variable position rotatable driving means in cooperative 45 relation with said rotatable element, making driving contact with any of said portions of said surface, mechanical means for varying the position of contact of said rotatable driving means, a pair of transparent segments on said rotatable element, an opaque segment separating said transparent segments on said rotatable element, a stationary light source in cooperative relation 50 with said transparent segments, said light source being adapted to be illuminated only during a short period of each revolution of said rotatable element, a pair of photoelectric cells on the opposite side of said rotatable element to and in cooperative relation with said light source to be operated by the light from said source and electromagnetic means in cooperative relation with said mechanical means for varying the position 55 of said variable position rotatable driving means and electrically connected to and under the control of said photoelectric cells to adjust the speed of said rotatable element in order to maintain synchronism and isochronism.

6. In combination: means including a rotatable element for reproducing an image from an image varied current, the different portions of the surface of said rotatable element being rotatable at different uniform speeds, electrical contact means carried on said rotatable element, 70

means including a rotatable driving member making driving contact with one of said portions of said surface at a time for imparting synchronous and isochronous motion speed to said rotatable element, suitable electrical circuits including a stationary brush in cooperative relation with said electrical contact means for producing corrective synchronizing currents when said rotatable element is not rotating synchronously, means in cooperative relation with said means for producing corrective currents and with said rotatable driving member for changing the position of said variable position rotatable driving member, and a centrifugal speed governing element in cooperative relation with said rotatable driving means in order to correct speed irregularities of said rotatable driving member.

7. A synchronism indicating means consisting of means including a rotatable element for reproducing an image from an image varied current, an electrical contact strip placed at a synchronism indicating point on said disk, electrical means in cooperative relation with said strip for transmitting a periodic current received from a distant station through said contact strip when said rotatable element is in synchronism and a synchronism indicating means in cooperative relation with said electrical means which is actuated by said current when said contact strip is in contact with said electrical means when said current is transmitted.

8. A television synchronizing apparatus consisting of means including a rotatable element for reproducing an image from an image varied current, the different portions of the surface of said element being rotatable at different uniform speeds, a variable position friction drive in cooperative relation with said rotatable element and making driving contact with any of said portions of said surface to impart uniform speed thereto, a centrifugal speed governor in cooperative relation with said variable position friction drive to vary the position of said friction drive to correct speed irregularities therein, electromagnetic-mechanical means for operating said variable position drive and electrical contact elements carried on said rotatable element in electrical cooperation with said electromagnetic-mechanical means for operating said variable position drive, in order to maintain said rotatable element in synchronism by speed adjustment.

9. In combination: means including a rotatable element for reproducing an image from an image varied current, the different portions of the surface of said element being rotatable at different uniform speeds, speed control electrical contact elements carried on said rotatable element, electromagnetic-mechanical means in cooperative relation with and under control of said speed control contact elements, a variable position friction drive in cooperative relation with said electromagnetic-mechanical means to vary the position of said variable position rotatable drive, said drive making driving contact with any of said portions of said surface, a motor controlling means in cooperative relation with said electromagnetic-mechanical means for varying the speed of said motor and a centrifugal speed governor in cooperative relation with said variable position drive to correct irregularities in the speed of said rotatable element.

10. A television synchronizing system consisting of means including a rotatable element for transmitting an image varied current, means associated with said rotatable element for interrupting said image varied current periodically

during a fraction of each revolution of said rotatable element, means including a second rotatable element for converting said image varied current into an image, synchronizing means in cooperative relation with said second rotatable element and operated by separate energy, means associated with said second rotatable element for holding open a synchronizing circuit by means of and during the flow of said image varied current and means for closing said synchronizing circuit during said interruptions.

11. A television apparatus consisting of a rotatable element, means for rotating said rotatable element, a pair of current influencing segments borne on said rotatable element, a non-influencing segment separating said segments and stationary synchronism controlling means in cooperative relation with said current influencing segments and said means for rotating said rotatable element, said noninfluencing segment being disposed opposite said stationary synchronism controlling means when a synchronizing current is received while said rotatable element rotates synchronously in order that said current influencing segments may be prevented from influencing said stationary synchronism controlling means when said rotatable element rotates in synchronism.

12. A television apparatus consisting of means including a rotatable element for reproducing an image from an image-modulated electric current, the different portions of the surface of said rotatable element moving at different uniform speeds, contact means borne on said rotatable element including a pair of arcuate contact segments, an insulating interval separating said arcuate contact segments, stationary contact means including a brush normally in position on said insulating interval when said rotatable element rotates in synchronism, a pair of electromagnetic elements, means for furnishing a periodic synchronizing current operatively connected to said brush and to said pair of electromagnetic elements, a variable position rotatable driving means making driving contact with any one of said portions of said surface of said rotatable element at a time and a clutch in cooperative relation with and operated by said pair of electromagnetic elements and connected with said variable position rotatable driving means in order to shift said driving means to engage any one of the said different portions of said surface to cause said rotatable element to rotate in synchronism.

13. A television apparatus consisting of means including a rotatable element for reproducing an image from an image modulated current, the different portions of a surface of said rotatable element being rotatable at different uniform speeds, a rotatable driving means in cooperative relation with said rotatable element and making driving contact with any of said portions of said surface at a time, electrical contact means borne on said rotatable element including two contact segments, an insulating interval disposed between said segments, a stationary contact brush normally making contact with said insulating interval when said rotatable element rotates in synchronism, shifting means for shifting the position of said rotatable driving means to attain and maintain said rotatable element in synchronism and means for operating said shifting means in cooperative relation therewith and electrically connected to said electrical contact means and said stationary contact brush in or-

der to cause said rotatable element to rotate synchronously.

14. A television apparatus consisting of means including a rotatable element for reproducing an image from an image-modulated current, the different portions of a surface of said rotatable element being rotatable at different uniform speeds, a rotatable driving means in cooperative relation with said rotatable element and making driving contact with any of said portions of said surface at a time, electrical contact means borne on said rotatable element including two contact segments, an insulating interval disposed between said segments, a stationary brush in cooperative relation with said segments and said insulating interval, said brush being situated on said insulating interval during synchronism, two electrical contact rings borne on said electrical rotatable element and connected to said contact segments, a pair of stationary brushes making contact with said contact rings, a clutch engaging said rotatable driving means to bring said driving means in contact with said different portions of said surface, electromagnetic means in cooperative relation with and operating said clutch and connected by suitable circuits to and controlled by said contact segments said electrical contact brushes and said contact rings in order to maintain said rotatable element in synchronism.
15. A television apparatus consisting of means including a rotatable element for forming an image from an image modulated electric current, means for uniformly rotating said rotatable element, synchronizing means including suitable electrical circuits and a controlling switch for operating said means for uniformly rotating said rotatable element at synchronous speed and a speed governing means operatively connected to said controlling switch to close said switch and circuits when said rotatable element is rotated at approximately synchronous speed.

16. An automatic television synchronizing apparatus consisting of a motor, a longitudinally shiftable shaft rotated by said motor, a rotatable driving element slidably mounted upon said shaft and being unrotatable relatively therewith, a rotatable scanning element, the different portions of a surface of said scanning element being movable at different uniform speeds, said rotatable driving element making driving contact with any one of said different portions of said surface at a time, a centrifugal speed governor in cooperative relation with said shaft in order to longitudinally shift said shaft in accordance with speed variations to bring said rotatable driving element into new driving positions, a clutch engaging with and acting to shift said rotatable driving element to different driving positions, electromagnetic means operating said clutch and suitable electrical switching means in cooperative relation with said rotatable scanning element and connected by suitable circuits to said electromagnetic means to operate said clutch in accordance with speed variations occurring in said rotatable scanning element.

17. An automatic television synchronizing apparatus consisting of a motor a hollow shaft rotatable by said motor, a second shaft in cooperative relation with said hollow shaft and making slidable engagement in the hollow of said hollow shaft, said shafts being relatively unrotatable with each other, a rotatable driving element slidably mounted upon said second shaft and being unrotatable relatively thereto, a rotatable scanning element the different portions of a

surface of which move at different uniform speeds, said rotatable driving element making driving contact with any of said different portions of said surface at a time, a centrifugal speed governor in cooperative relation with said second shaft and acting to cause said shaft to enter more or less deeply in said hollow of said hollow shaft to move said rotatable driving element to contact with different portions of said surface to correct speed irregularities therein, a clutch for shifting said rotatable driving element into contact with any of said portions of said surface, electromagnetic means for operating said clutch and suitable electrical switching means in cooperative relation with said rotatable scanning element and connected by suitable circuits to said electromagnetic means to operate said clutch in accordance with speed variations in said rotatable scanning element.

18. An automatic television synchronizing apparatus consisting of means including a rotatable scanning element for forming an image from an image-modulated current, means for rotating said rotatable element at uniform speed, synchronizing means for maintaining said rotatable element in synchronism, a switch connected to and controlling said synchronizing means in order to cut said synchronizing means in or out of circuit and a speed governing means in cooperative relation with said switch to bring said synchronizing means into action when said rotatable element rotates at approximately synchronous speed.

19. An automatic television synchronizing apparatus consisting of means including a rotatable scanning element for forming an image from an image-modulated current, a rotatable driving element slidably mounted upon a shaft and making driving contact with the surface of said rotatable scanning element, the different portions of the surface of said scanning element being rotatable at different uniform speeds and said driving element making driving contact with any of said portions of said surface at a time, a clutch for shifting the position of said driving element to bring it into contact with any of said portions, electromagnetic means for operating said clutch, suitable switching means in cooperative relation with said rotatable scanning element and connected by suitable circuits to said electromagnetic means to operate said clutch in accordance with speed irregularities in the motion of said rotatable scanning element.

20. An automatic television synchronizing apparatus consisting of a uniformly rotatable driving means, a centrifugal speed governor in cooperative relation with said driving means, to correct speed irregularities therein, a variable position rotatable contact element in cooperative relation with and driven by said driving means, means for shifting the position of said variable position rotatable contact element to impart different desired uniform speeds to said rotatable contact element, means including a rotatable scanning element for reproducing an image from an image modulated current, the different portions of a surface of said scanning element being rotatable at different uniform speeds and being in cooperative relation with said variable position contact element, electrical means including suitable contacts borne on said rotatable scanning element in cooperative relation with said means for shifting and a switch in cooperative relation with and controlling said electrical means and in cooperative relation with and to be operated by

said centrifugal speed governor to close said switch when said rotatable scanning element rotates at approximately synchronous speed.

21. In combination: a rotatable element, 5 means in cooperative relation with said rotatable element for reproducing an image from an image varied current, the different portions of the surface of said rotatable element being rotatable at different uniform speeds, a variable position rotatable driving means in cooperative relation with said rotatable element making driving contact with any of said portions of said surface to drive said element at any uniform speed and means for producing corrective synchronizing adjustments 10 in the position of said variable position rotatable driving means in cooperative relation with said rotatable element and said variable position rotatable driving means where said rotatable element is not rotating synchronously.
- 20 22. A claim in accordance with claim 21 but in which said means for producing corrective synchronizing adjustments includes transparent portions on said rotatable element.
23. A claim in accordance with claim 21 but 25 in which said means for producing corrective synchronizing adjustments includes transparent portions borne on said rotatable element in co-

operative relation with a stationary light source and photoelectric cells.

24. A claim in accordance with claim 21 but in which said means for producing corrective synchronizing adjustments includes transparent portions 5 borne on said rotatable element and stationary photoelectric cells in cooperative relation with electromagnetic means.

25. In combination: a rotatable element, means 10 in cooperative relation with said rotatable element for reproducing an image from an image varied current, the different portions of the surface of said rotatable element being rotatable at different uniform speeds, a variable position rotatable driving means in cooperative relation with said rotatable element making driving contact with any of said portions of said surface to drive said element at any uniform speed and means for producing corrective synchronizing currents 15 when said rotatable element is not rotating synchronously, and means in cooperative relation with said means for producing corrective currents and with said variable position rotatable driving means to re-establish synchronism by changing the position of said variable position rotatable 20 driving means.

ALOYSIUS J. CAWLEY.
